(57) **CLAIM**

The ornamental design for a carabiner with strap attachment, as shown and described.

DESCRIPTION

FIG. 1 is a front elevation view of a carabiner with a strap attachment showing my new design.

FIG. 2 is a rear elevation view of FIG. 1.

FIG. 3 is a right side elevation view of FIG. 1.

FIG. 4 is a left side elevation view of FIG. 1.

FIG. 5 is a top plan view of FIG. 1.

FIG. 6 is a bottom plan view of FIG. 1.

FIG. 7 is a rear perspective view of FIG. 1.

FIG. 8 is a rear elevation view of a second embodiment of a carabiner with a strap attachment.

FIG. 9 is a front elevation view of FIG. 8.

FIG. 10 is a top plan view of FIG. 8; and,

FIG. 11 is a bottom plan view of FIG. 8.

The right side elevation view of the embodiment of FIG. 8 is a mirror image of FIG. 3; the left side elevation view of the embodiment of FIG. 8 is a mirror image of FIG. 4. The gate strap, pin holes and lever, which are shown in broken lines, illustrate environment only and do not form part of the claimed design.
